UNITED STATES PATENT OFFICE.

GERSON KRICHEVSKI AND ABRAHAM EDMONDS, OF NEW YORK, N. Y.

ESCAPEMENT FOR WATCHES.

SPECIFICATION forming part of Letters Patent No. 321,611, dated July 7, 1885.

Application filed January 19, 1885. (No model.)

To all whom it may concern:

Be it known that we, GERSON KRICHEVSKI and ABRAHAM EDMONDS, both of the city, county, and State of New York, have invented 5 certain new and useful Improvements in Escapements for Watches, of which the following is a full, clear, and exact description.

The object of our invention is to reduce the friction and increase the durability of the escapement-movement of watches; and our invention consists, principally, of a curved or circular detent or locking piece for the escapement-wheel.

The invention also consists in giving said 15 detent or locking piece a circular movement for releasing the teeth of the escapement-wheel.

The invention consists, also, of the means employed for rotating the escapement-detent, 20 and of the construction, arrangement, and combination of parts, all as hereinafter described and claimed.

Reference is to be had to the accompanying drawings, forming part of this specification, 25 in which similar letters of reference indicate corresponding parts in all the figures.

Figure 1 shows our new escapement-movement, the parts thereof being in the position they occupy when the escapement-wheel is held by the locking-piece or escapement-detent, the latter shown in section on line $x-x$ of 30 Fig. 5. Fig. 2 shows the same, the parts being in the position they occupy just as a tooth of the escapement-wheel is released by the detent or locking piece. Fig. 3 shows the same 35 after the tooth has passed the detent, showing a tooth of the escapement in engagement with the impulse-pallet to the balance-wheel. Fig. 4 shows the same, the parts being in the 40 position they occupy at the time the disengaging-pallet passes the pawl or spring upon the escapement-lever during the return movement of the balance-wheel, and Fig. 5 is an enlarged edge view of the movement, showing 45 the hair-spring and part of the balance-wheel. Fig. 6 is a detail view.

A represents the lower plate, and B the balance-wheel, of the watch-movement, and C represents the escapement-wheel. k is the 50 staff on which the balance-wheel B is secured,

and on the staff k is secured the hair-spring x . (Shown in Fig. 5.) The staff k is provided with the disk-roller l , which is formed with the disengaging-pallet m , to act in connection with the escapement-lever e and spring n , as 55 hereinafter described, to vibrate the lever n . The staff k is also provided with the larger disk-roller q , formed with the impulse-pallet p , that intercepts the teeth of the escapement-wheel C, and causes the wheel to impart new power 60 to the balance-wheel.

a is the escapement-detent or locking-piece, pivoted on its axis b , and made practically semi-cylindrical or meniscus-shaped in cross-section at the point where the teeth of the escapement-wheel come in contact with it. It is formed to present the curved horn or surface a' as the point of contact with the teeth of the escapement-wheel.

The detent a is rotary reciprocated on its 70 axis by the vibrations of the lever e acting through the disk or arm c , secured to the detent, and the pin c' , secured to the disk and entering the slot f made in the lever e . The slot f and pin c' may be reversed, if desired. 75

The lever e is pivoted at e^2 , is held pressed constantly toward the escapement-wheel by the spring h , the free end of which presses against pin g' , secured to the lever, and the said lever is provided with the above-mentioned spring n , that reaches past the free end of the lever, so as to stand normally in the path of the disengaging-pallet m , as shown clearly in the drawings.

The action of our escapement-movement is 85 as follows: The escapement-wheel being held by the detent a , and the balance-wheel B swinging in the direction of the small arrows, (shown in the drawings,) the disengaging-pallet m on the fixed disk l will strike the end of the delicate spring n and carry the lever e to the dotted line marked e' in Figs. 1 and 3. In moving to this position the lever e will turn the holding piece or detent a and bring the curved portion a' thereof from in front of the tooth of the escapement-wheel C and let the tooth pass. At the same time that the tooth passes the detent a the impulse-pallet p , fixed to the roller-disk q , is carried to the dotted line marked r in Fig. 1, and the instant the 90 95 100

tooth of the escapement-wheel leaves the curved detent *a* the tooth of the escapement-wheel nearest the line marked *r* will strike the pallet *p* and throw the balance-wheel *B*, 5 and staff *h*, and disks *q l*, and pallets *m p* partly around the circle, or nearly a whole revolution. The instant the pallet *m* leaves the end of the spring *n* the lever *e* is forced back by the spring *h* to its original position, that shown in 10 full lines in Figs. 1 and 3, which movement of the lever *e* will turn the locking-pallet *a* in position to intercept the next tooth of the escapement-wheel *C*. The hair-spring *x* will now return the balance-wheel, staff *h*, disks *l* 15 *q*, and pallets *p m*, the spring *n* yielding to permit the pallet *m* to pass beyond it and past the lever *n* ready for another vibration.

A pin, *s*, is fixed in the plate *A* of the watch-

movement to prevent the lever *n* and detent *a* from being moved too far, and a pin, *s'*, is fixed in the plate *A* below the disk *q* to prevent vibration of the lever *e*. 20

Having thus described our invention, we claim as new and desire to secure by Letters Patent—

1. The detent *a*, connected with the lever *e* by an arm or disk, *c*, and pin *c'*, entering a slot in the lever, substantially as described. 25

2. The semicircular detent *a*, formed or provided with an arm or plate, *c*, substantially as 30 shown and described.

GERSON KRICHESKI.
ABRAHAM EDMONDS.
